UNITED STATES PATENT OFFICE.

HARRY J. VALENTINE, OF SAN FRANCISCO, CALIFORNIA, ASSIGNOR TO THE COLUMBIAN
HARDWARE COMPANY, OF CLEVELAND, OHIO, A CORPORATION OF OHIO.

DESIGN FOR A FACE-PLATE FOR REGISTERS.

No. 39,663.

Specification for Design.

Patented Nov. 3, 1908.

Application filed July 6, 1908. Serial No. 442,258. Term of patent 14 years.

To all whom it may concern:

Be it known that I, HARRY J. VALENTINE, a citizen of the United States, residing at San Francisco, in the county of San Francisco and State of California, have invented a new, original, and ornamental Design for Face-Plates for Registers, of which the following is a specification, reference being had to the accompanying drawing, forming part thereof, and which is the plan view of a face plate for registers showing my new design.

I claim.

The ornamental design for a face plate for registers, substantially as shown.

HARRY J. VALENTINE.
